[57] CLAIM

The ornamental design for a radial axis angle indicator, as
shown and described.

DESCRIPTION

FIG. 1 is a front, top and side perspective view of the radial
axis angle indicator embodying the design of the present
invention;

FIG. 2 is a front elevational view thereof;

FIG. 3 is a side elevational view thereof, the side opposite
being a mirror image of the side shown in FIG. 3;

FIG. 4 is a top plan view thereof; and,

FIG. 5 is a bottom plan view thereof.

The rear elevational view being plain.
